UNITED STATES PATENT OFFICE

EDWARD LACY SHELTON, OF MEMPHIS, TENNESSEE

COMBINED LICENSE-TAG MOUNTING AND SIGNAL AND TAIL LIGHT

Application filed January 24, 1929. Serial No. 334,787.

This invention relates to a combined license tag mounting and signal and tail light, and has for an important object thereof the provision of a device of this character which will support a license tag in such manner that it is fully illuminated, particularly when a tag of the type illustrated in my prior Patent, No. 1,694,832 is employed in connection therewith.

10 A further object of the invention is to provide a signal casing which may be very readily and cheaply constructed and in which a combined partition and illuminating element support is so mounted that access may be readily had thereto in order to change the illuminating elements or to effect any necessary repairs in connection therewith.

15 A still further object of the invention is to provide a novel and improved structure eliminating the difficulties ordinarily accompanying the provision of such structures with reflectors.

20 These and other objects I attain by the construction shown in the accompanying drawings, wherein for the purpose of illustration is shown a preferred embodiment of my invention and wherein:—

25 Figure 1 is a front elevation of a combined signal and license plate support constructed in accordance with my invention;

Figure 2 is a rear elevation thereof;

Figure 3 is a section on the line 3—3 of Figure 1;

Figure 4 is a section through the front and side wall sections of the casing removed;

Figure 5 is a front elevation of the rear wall and the bracket with the front and side wall sections removed;

Figure 6 is a section on the line 6—6 of Figure 1;

Figure 7 is a detail sectional view illustrating the manner in which the reflector acts to hold the lenses in position;

Figure 8 is a fragmentary edge elevation of the reflector.—

Referring now more particularly to the drawings, the numeral 10 indicates a plate having secured thereto a rearwardly and downwardly inclining arm or support 11 which is adapted at its lower end to engage

against a fender 12 rearwardly of the longitudinal crown thereof and support the plate from the fender in a vertical position. This plate will preferably have stamped thereon a State name and identification number, as indicated at 14, and is provided with slots 15 for the passage of securing elements, by means of which the license plate 16 is attached. At its upper end, the plate is provided with a reduced vertical extension 17, the marginal edges of which, together with the shoulders 18 formed at opposite sides of the extension upon the upper end of the plate, are flanged, as indicated at 19, so as to stiffen the plate and enable the extension to be offset forwardly, as indicated at 20.

These marginal flanges further serve as a hood, preventing the entrance of water, snow and the like between the upper edge of the license plate and the attaching plate 10 and thus prevent corrosion thereof.

The upper end of the extension is arcuately curved and seated against this extension is a cylindrical casing 21, the front wall 22 of which is provided with a lower lens opening 23 and upper lens openings 24 and 25 separated from one another by vertical and horizontal partition strips 26 and 27. The extension has similar lens openings 23a, 24a and 25a separated by similar partition strips 26a and 27a. Associated with the openings of the wall 22 is a lens 28, while associated with the wall of the extension is a lens 28a which will hereinafter be more fully described.

The circular wall of the casing 21 has formed therein at its lower end a longitudinally extending slot 29 within which is disposed a lens 30 having at its ends and sides flanges 31 seating upon the inner face of this wall. These flanges are retained in position by clamps 32, each of which engages the lens with one end and has its opposite end in slightly spaced relation to the inner face of the wall.

Disposed within and against the inner face of the wall and between the outer ends of the clamps is a reflector band 33 which has its ends engaged between the outer ends of the

clamps and the outer wall and which has at its side edges flanges 34 adapted to seat against the inner faces of the lenses 28, 28a to hold them against their respective walls.

The flange opposing the lens 28a is notched, as at 35, in alignment with the vertical partition, for a purpose presently to appear.

A combined reflector and illuminating element support is provided comprising a horizontal plate 36 shaped to conform to the partitions 27, 27a and having a central vertical wall arising therefrom, as indicated at 37, and adapted to oppose the partitions 26, 26a of the front and rear walls of the signal casing. The upper end of this vertical wall has a flange 38 adapted to abut the inner face of the reflector plate and fit thereagainst to steady this wall and retain the reflector plate against any tendency to sag, thus enabling its production from relatively thin material. The horizontal plate 36 has at its opposite ends apertured ears 39, the apertures of which align with openings formed in the opposite ends of the partitions 27, 27a and the corresponding lenses. The apertures of these ears are threaded for the reception of the securing elements, which are designated at 40, so that these securing elements serve to secure the sections of the casing to one another and to the partition and to hold the lenses against movement. This plate is further preferably provided with legs attaching it directly to the wall of the extension, as indicated at 41. This plate, it will be noted, divides the interior of the casing into a main lower compartment 42 and upper compartments 43 and 44. The horizontal plate carries sockets for illuminating elements for each of these compartments and these sockets have associated therewith contact elements 45 electrically connected to a multiple connection plug 46 mounted in a socket formed about the edges of an opening in the circular wall of the casing 21 and from which the plug is readily removable. The reflector 33 in alignment with this opening has an opening through which the plug may pass.

The portions of the lenses 28 and 28a opposing the compartment 23 are preferably red and green respectively, those opposing the compartment 43 red and those opposing the compartment 44 amber or white. The compartments 43 and 44 may constitute signal compartments and may be operated from any suitable signal switches, while the compartment 42 constitutes a tail light compartment.

It will be obvious that a structure of this character may be very readily and cheaply produced and is very readily repaired. If the surface of the reflector band becomes dirty, it may be readily cleaned or replaced by simply removing the securing elements 40 which secure the casing 21 to the partition and illuminating support. This permits the

reflector and this casing wall to be bodily removed when the reflector may be readily slid out of the casing by movement axial to the casing and cleaned or replaced. A similar operation affords access to the illuminating elements for replacement or repair and also permits replacement of the front lens of the signal light. The rear lens or that lens carried by the wall 17 may be removed by removing the bracket from the extension 17.

Since the construction hereinbefore set forth is capable of a certain range of change and modification without materially departing from the spirit of the invention, I do not limit myself to such specific structure except as hereinafter claimed.

I claim:—

In a signal light construction, a cylindrical casing having the opposite ends thereof open, an annular reflector mounted in the casing and engaging the inner walls thereof, a license plate bracket, said license plate bracket having an upstanding flanged ring mounted thereon, the forward end of said casing seating in said casing, said casing having an opening through the bottom wall thereof, a lens removably mounted in said opening, a downwardly inclined arcuate member having reverted end portions mounted in said casing and above said wall opening, said member having outwardly extending ears for engagement with said bracket whereby to hold the casing thereon, a substantially vertically disposed arcuately inclined reflector secured at one end to said first arcuate member and at the opposite end engaging said annular reflector, said first member and second member dividing said casing into light compartments, lamps mounted in each compartment, lenses mounted in the casing and at the opposite end portions of each compartment, and removable means for holding the lenses against the opposite end portions of the casing.

In testimony whereof I hereunto affix my signature.

EDWARD LACY SHELTON.
